FIG 8

INVENTOR:

Henry A. Church.

by Geo. H. Remington - 117y.

UNITED STATES PATENT OFFICE.

HENRY A. CHURCH, OF PROVIDENCE, RHODE ISLAND.

ROLLER-CHAIN CAP.

SPECIFICATION forming part of Letters Patent No. 289,618, dated December 4, 1883.

Application filed September 24, 1883. (No model.)

To all whom it may concern:

Be it known that I, HENRY A. CHURCH, a citizen of the United States, residing at Providence, in the county of Providence and State 5 of Rhode Island, have invented certain new and useful Improvements in Roller-Chain Caps; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This my present invention relates to certain improvements in ornamental or jewelry chains of the class generally known among jewelers as "roller-chains," such chains being composed of a series of small hollow beads or 20 units arranged longitudinally and alternately with another series of units, which in turn alternate with another series, and so on, until the desired width of chain is produced, the whole being held together by a series of bent 25 wires or staples, the units being adapted to each receive two lengths of said wire.

My invention consists in a new and improved manner of covering or capping the units which 30 form one side or edge of the chain, all as will be more fully hereinafter set forth.

To illustrate my invention I have prepared the annexed sheet of drawings, in which—

Figure 1 represents a side view of a portion of a roller-chain, the top row of units being 35 provided with my improved cover or cap. Fig. 2 represents the same with the caps removed. Fig. 3 is the same as Fig. 2, except the twisted ends of the stringing or binding wires have not been clipped. Fig. 4 represents a vertical longitudinal section through the chain, showing 40 the manner of building it up, the ends of the wires, however, not being twisted or clinched. Fig. 5 represents a view similar to Fig. 1, but showing two of the unit coverings or caps in 45 section and secured to said units. Fig. 6 represents a bottom view of the lower outside unit, showing the bent end of the wire staple. Fig. 7 represents a bottom view of an intermediate 50 unit. Figs. 8 and 9 represent sectional and top views, respectively, of my improvement. Fig. 10 represents a top view of modification of the cap, all the views being enlarged.

The following is a detailed description of my invention and the manner of using the same:

A in the drawings represents a portion of a 55 chain composed of intermediate units, A', bottom units, B, top units, B', improved cap or covering B' for said top units, and the bent wires or staples b. The bottom units, B, have two openings, b², therein, into which the wire 60 staple b is inserted, as fully shown. (See Fig. 4.) When, after passing said staple through the intermediate units, A', the ends are inserted through the top units, B², (the latter being smaller than the other units,) after which the 65 ends of the wire staples are twisted together, as shown at b³, Fig. 3, and then cut off flush with the upper edge of the units B², as shown in Fig. 2. The chain is now ready to receive the metallic coverings or caps B', which are of 70 the form shown in Figs. 8 and 9, the top side or end thereof having a convex center, b⁴, rim b⁵, and parallel sides b⁶. Said caps, after being placed over the units B², are secured both together by soldering, burnishing, or any other 75 well-known means, thus completing the chain. The caps B' are made from blanks by suitable dies, &c., in a manner common to other analogous work, a description thereof not being deemed essential to this specification. 80

My object in making the center of the cover or cap convex, as at b⁴, is to approximate in form and appearance to the metallic units B of the opposite side of the chain, which latter have the staples b passing through them, the bend 85 thereof being exposed, as shown in Figs. 4 and 6.

I have shown in Fig. 10, at b⁷, a modification of the center of the cap B', which may be made in said caps, although in assembling the caps more time would be consumed in placing them 90 properly than would be the case with the round center caps shown in Figs. 8 and 9.

I am aware that it is not new to cover the end units, and I therefore do not claim such, broadly; but

What I do claim, and desire to secure by Letters Patent, is—

1. In a roller-chain, the combination, with the intermediate units which form the body of the chain, of outside top and bottom units, the latter adapted to receive and retain the wire staples which unite the several units together, the top units adapted to receive a covering or cap having parallel sides, the end thereof be-

ing formed to approximate the outer end of the opposite and reverse unit, substantially as shown, and for the purpose described.

2. In a roller-chain, the combination, with the 5 intermediate units, A', end units, B B², united by the wire staples b, of the unit covering or cap B', having a closed end, consisting of the convex center b⁴, rim b⁵, and parallel sides b⁶, substantially as shown and described.

10 3. The cap B', consisting of the parallel sides

b⁹, rim b⁵, and convex center b⁴, all made from a piece of sheet metal, and adapted to cover or cap the upper series of units, B², of the roller-chain A, as herein shown and described.

In testimony whereof I have affixed my signature in presence of two witnesses. 15

HENRY A. CHURCH.
